UNITED STATES PATENT OFFICE

NORMAN EUGENE DELL, OF BUFFALO, NEW YORK

HYDROPOWER GENERATING MACHINE

Application filed September 13, 1930. Serial No. 481,784.

My invention relates to improvements in hydro-power generating machines, and the object of my invention is to devise a machine comprising a submersible chamber contained within a body of water and adapted to lower and raise itself in such body of water through the alternative admittance of water and air into the chamber.

A further object of my invention is to position a reciprocable piston within the chamber through the movement of which water and air is alternatively admitted to the chamber, and to utilize a hydraulic ram mechanism for actuating the piston, the power for actuating such ram mechanism being supplied independently of the downward and upward movement of the chamber in the body of water.

My invention consists of a hydro-power generating device all as hereinafter more particularly described and illustrated in the accompanying drawings in which:—

Figure 1 is a longitudinal vertical cross sectional view through a water containing tank and my machine, the water not being shown in order to avoid confusion in the drawings.

Figure 2 is a vertical cross sectional view taken through line 2—2, Figure 1, my mechanism being shown at the upper end of its travel, and

Figure 3 is a plan view of a fragmentary portion of my mechanism.

Like characters of reference indicate the corresponding parts in the different views in the drawings.

The container 1 illustrated in Figures 1 and 2 is preferably imbedded in the ground, and can be of any desired area or depth dependent upon the size of my mechanism contained therein.

In practice it will be found desirable to construct the container of much greater depth than that shown in the drawings, in order that my mechanism may have a considerable length of travel in its upward and downward movement.

It is to be understood that the container as illustrated in Figures 1 and 2 is of course filled with water up to a close vicinity of its

upper edge, although I have not shown such tank as filled in the drawings in order to avoid obscurity.

In the vicinity of the ends of the container 1 and contained within such container, I position a pair of standards 2 which support a plurality of horizontally extending hydraulic ram cylinders 3, the rams 4 in the cylinders of each standard 2 support a substantially rectangular frame 5. By this construction a pair of frames 5 are provided, such frames 5 having a horizontal reciprocable movement under the reciprocal movement of the hydraulic rams 4.

I have not illustrated, nor will specifically describe any particular hydraulic pump mechanism for actuating the rams, as it will be readily appreciated by those conversant with up-to-date hydraulic mechanics that a hydraulic high pressure pump actuated by an electric motor or other suitable power generating means can now be supplied in which great hydraulic pressures can be exerted in comparison to the horsepower of the power-generating means actuating the pump. The hydraulic ram cylinders 3 are connected to such a pump mechanism by the fluid pipes 6.

Centrally between the inner faces of the frames 5, I position a battery of cylinders or chambers, 7. In the drawings twelve cylinders are shown, these cylinders facing each frame 5. Each cylinder contains a piston 8 secured to a piston rod 9 which projects through an orifice 10 in the head plate 11 of each cylinder.

The cylinders are contained within a pair of frames 12 which surround each section of the cylinders, and the inner facing ends of the cylinders in the sections are secured together and positioned by a plurality of saddle plates 13. The inner ends of the cylinders are open, collars 14 being furnished. The outer ends of the piston rods 9 are connected to a pair of plates 15 which are provided with brackets 16 upon their corners and containing running wheels 17 which extend into channel shaped tracks 18 positioned longitudinally to my mechanism and carried upon the upper and lower faces of the frames 12.

From this description it will be seen that

the plates 15 together with the outer ends of the piston rods 9 are rollably supported by the tracks 18 for reciprocable movement. The plates 15 are in turn connected to the frames 5 by a plurality of brackets 19 which are mounted upon the outer faces of the plates 15 and carry rollers 20 which engage the forward and rear faces of the vertical edges of the frames 5, whereby the plates 15 may freely roll upwardly and downwardly upon the frames 5.

Extending transversely of the top of my assembled cylinders I furnish a bridge piece 21 which is secured to the upper tracks 18 15 intermediately of their length, and extending from this bridge piece I provide a connecting rod 22 by means of which the upward and downward movement of my mechanism is harnessed in any required manner. 20 The sides of the tank 1 are provided upon their inner faces with vertical tracks 24 into which running wheels 25 mounted upon the sides of the frames 12 extend.

For admitting air into the cylinders or 25 chambers 7 under the reciprocal movement of the pistons 8 I furnish breather pipes 23 which are connected to the cylinders through the head plates 11.

The operation of my device is as follows:— 30 Assuming that my mechanism is at the surface of the water as illustrated in Figure 2, the pistons 8 will be at the opposite ends of their strokes to that illustrated in Figure 1, in other words the water will have 35 been expelled from the cylinders through their open ends and air contained within the cylinders between the head plates 11 and the pistons, such air of course being admitted through the breather pipes 23. The 40 movement of the pistons into this position from the position illustrated in Figure 1 has been accomplished through the forward or inward movement of the frames 5, plates 15, piston rods 9 and pistons 8 under the 45 pressure movement of the hydraulic rams 4 in the cylinders 3.

When my mechanism has reached the surface of the water wherein the pistons 8 are at the outer end of their strokes as explained 50 in the preceding paragraph, the hydraulic rams 4 are moved inwardly to their initial position illustrated in Figure 1, thereby moving the frames 5, plates 15, piston rods 9 and pistons 8 in the corresponding directions 55 so that the air in the cylinders is expelled through the breather pipes 23 and water admitted through the open ends of the cylinders. As soon as this occurs the mechanism will immediately sink, the rollers 20 upon the brackets 19 rolling down the sides of the frames 5, and the rollers 25 on the frames 12 rolling down the tracks 24.

When the mechanism reaches the bottom 60 of the tank the hydraulic rams 4 are again actuated, the actuation of such rams being

controlled and synchronized by the movement of my mechanism, and the frames 5, plates 15, piston rods 9 and pistons 8 are moved inwardly or towards each other, thus expelling the water from the cylinders and permitting air to enter such cylinders through the breather pipes 23, so that my mechanism again becomes buoyant and rises to the surface of the water, the rollers 20 rolling upon the frames 5, and the rollers 25 rolling in the tracks 24.

It will be understood that little hydraulic pressure will be required when my mechanism is at the surface of the water in order to move the pistons to expel the air from the cylinders to admit the water, as the only power required will be that necessary to overcome the friction of the pistons within the cylinders. When the mechanism is submerged greater hydraulic pressure will be necessary 85 in order to move the pistons forwardly against the water pressure for the admittance of air.

It will be understood that although in the drawings I have shown my device of limited 90 size and form it can be so constructed that the mechanism can be submerged to a considerable depth and made sufficiently buoyant when submerged through a comparatively small hydraulic pressure, that a tremendous 95 buoyancy pressure may be produced upon the expulsion of the water from the submerged cylinders and although I have shown and described a particular embodiment of my invention, it is to be understood that I 100 can make such changes and alterations as I may deem necessary from time to time without departing from the spirit of my invention as set forth in the appended claims.

What I claim as my invention is:

1. In a hydro-power generating machine of the character described, a submersible cylinder contained within a body of water and adapted to alternately float and submerge, a piston reciprocable in the cylinder, a closure for one of the cylinders, an air breather pipe connected to the closed end of the cylinder, and means actuated independently of the upward and downward movement of the cylinder for reciprocating the piston within the cylinder.

2. In a hydro-power generating machine of the character described, a pair of opposed horizontally extending submersible cylinders contained within a body of water and adapted to alternately float and submerge, a closure for one end of each cylinder, a piston reciprocable in each cylinder, a piston rod extending from each piston to the exterior of its cylinder, an air breather pipe connected to the closed end of each cylinder, a pair of reciprocable frames submerged in the water, hydraulic rams for reciprocating the frames and members rollably connected to the frames for vertical movement and to which

the outer ends of the piston rods are connected.

3. In a hydro-power generating machine of the character described, a plurality of opposed horizontally extending submersible cylinders contained within a body of water and adapted to alternately float and submerge, a frame in which the cylinders are contained, a closure for one end of each cylinder, a piston reciprocable in each cylinder, a piston rod extending from each piston to the exterior of its cylinder, an air breather pipe connected to the closed end of each cylinder, a pair of reciprocable frames submerged in the water, hydraulic rams for reciprocating the frames, members rollably connected to the frames for vertical movement and to which the outer ends of the piston rods are connected, and tracks mounted upon the frame containing the cylinders and upon which the members are rollably supported.
